UNITED STATES PATENT OFFICE.

JOHN ANDERSON, OF NEW YORK, N. Y.

DESIGN FOR MATERIAL FOR GORED SKIRTS.

Specification forming part of Design No. 6,829, dated August 26, 1873; application filed June 23, 1873.

To all whom it may concern:

Be it known that I, JOHN ANDERSON, of the city, county, and State of New York, have invented a new and original Design for Printed Material for Gored Skirts, of which the following is a specification:

The accompanying drawing represents the design printed on a piece of muslin partly unrolled.

The lines which indicate the lines of division between the gores where the material is to be cut are shown at *b*.

The design is printed in succeeding sections, each the counterpart of the other, on a roll of muslin or other material, each section consisting of a central full or complete gore, *A*, with a half-gore, *B*, on each side, the broadest

or bottom portion of the latter in each section occupying a position the reverse of that of the same portion of the central gore. The gores can be printed, in addition, with any ornamental pattern, as shown at *a*, and on any material, such as muslin, linen, felt, or Canton or cotton flannel, using the smooth or reverse side of such flannel.

What I claim, and desire to secure by Letters Patent, is—

The design for printed material for gored skirts herein shown and set forth.

JOHN ANDERSON.
